UNITED STATES PATENT OFFICE.

OSCAR V. PAYNE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

DRIVE FOR PATTERN MECHANISM FOR LOOMS.

Application filed August 1, 1928. Serial No. 296,704.

This invention relates to improvements in driving mechanism for looms and it is the general object of the invention to drive the loom in such a way that the picking motions will not interfere with the smooth operation of the harness controlling mechanism.

In the so-called Knowles loom, an example of which is seen in patent to Knowles No. 134,992, it is customary to have a so-called head provided with an upright shaft the upper end of which drives a pair of cylinders rotating in opposite directions and acting to raise or lower the harnesses through cooperation with vibrator gears and connectors. The lower end of the upright shaft is ordinarily connected to the bottom shaft of the loom by gearing which preferably gives the head a dwell as the lay is moving backwardly so that the shuttle may have ample time to cross the lay. The bottom shaft carries the ordinary picking arms which are located one on each side of the loom and the driving unit for the loom is located at that side of the loom opposite the upright shaft or head motion. The picking motion on that side of the loom near the head occasionally causes the bottom shaft to twist during the time that the picking ball is moving up the picking cam. As soon as the picking ball has passed over the top of the cam, however, the strain to which the shaft was previously subjected is released and the shaft immediately springs forward to assume its normal form. This sudden forward movement of the shaft due to the relieving of the strain thereon gives a quick motion to the upright shaft and all of the driving and driven parts connected thereto with the result that breakage occurs in one or another of these parts.

It is an important object of my present invention to provide an auxiliary shaft for driving the head motion, said shaft being independent of the bottom shaft and also the top or crank shaft of the loom, but deriving its motion from gearing a part of which is secured to the bottom shaft at a point preferably though not necessarily between the source of power and that part of the picking motion secured to the bottom shaft and adjacent the source of power. In this way the drive for the auxiliary shaft is not subjected to any twist incident upon the

operation of the picking motion on the head end of the loom. The head operates in a smooth manner with the result that the aforementioned parts are not subjected to breakage.

I find that the position of the upright shaft and also the position of other parts of the loom cannot very conveniently be changed with respect to the bottom shaft when the auxiliary shaft is properly positioned to cooperate with the upright shaft it happens that the axis of said auxiliary shaft lies within the path of movement of the picking ball, so that said auxiliary shaft, if the same were straight throughout its length, would be struck by the picking arm. It is a further object of my present invention to offset the shaft at points in alignment with the picking arm on the bottom shaft and to dispose the offset in such a direction relatively to the picking arm as will permit the latter to operate without interference with the auxiliary shaft.

This latter feature of my invention is equally effective whether the loom be an automatic loom having drop boxes on one end only, or whether the loom be of the so-called pick and pick type wherein the bottom shaft rotates once every pick of the loom. This is because of the fact that the upright shaft which drives the head is given a complete revolution every pick of the loom and the auxiliary shaft is so related to the bottom shaft by gearing that it also will be given a complete revolution every pick of the loom. For this reason the offset will always be turned away from the picking arm when the latter is moved toward the auxiliary shaft.

It is customary to provide the dwell previously mentioned for the shuttle by introducing elliptical gears between the bottom shaft and the upright shaft and in carrying my present invention into effect I provide elliptical gears between the bottom shaft and the auxiliary shaft, said gears as shown herein being in the ratio of 2 to 1. It is desirable under certain conditions to be able to change the timing of the head and this is ordinarily accomplished by changing the setting of the elliptical or eccentric gear on the bottom shaft. In the arrangement set

forth herein I make provision for this adjustment in such a way as will not interfere with the clearances necessarily existing between the picking arms and the auxiliary shaft.

With these and other objects in view which will appear as the description proceeds, my invention resides in the combination and arrangement of parts hereinafter described 10 and set forth in the claims.

In the accompanying drawings wherein I have shown the invention as applied to a Knowles loom,

Fig. 1 is a rear elevation of a loom having 15 my invention applied thereto,

Fig. 2 is a horizontal section taken on line 2—2 of Fig. 1, certain parts being removed for the sake of clearness,

Fig. 3 is an enlarged vertical section on 20 line 3—3 of Fig. 2,

Fig. 4 is an enlarged vertical section on line 4—4 of Fig. 2,

Fig. 5 is an enlarged section on line 5—5 25 of Fig. 2 showing the means for adjusting the elliptical gear on the bottom shaft,

Figs. 6 to 8 are diagrammatic views showing the positions of the picking arm and offset in the auxiliary shaft in the several 30 positions they may assume for an ordinary loom wherein the bottom shaft makes one revolution for every two picks of the loom, and

Figs. 9 to 11 are a similar series of views 35 illustrating the parts in a pick and pick loom wherein the picking mechanism at each end of the loom is actuated every pick of the loom, the bottom shaft in this instance also making a complete revolution every second pick of the loom.

40 Referring particularly to Figs. 1 and 2 I have shown a loom frame 10 having arches 11 to support a head H which may be substantially the same as that shown in the previously mentioned patent to Knowles No. 45 134,992. Said head motion includes in its construction a pair of upper and lower bevel gears 12 and 13, respectively, which mesh with similar gears 14 and 15, respectively, secured to an upright shaft 16. Vibrator 50 levers 17 pivoted around a heel pin 18 are determined as to their vertical position by a pattern chain 19 which preferably receives an angular motion each pick of the loom. By means of vibrator gears 20 the connectors 55 21 are moved either to the right or left as viewed in Fig. 1, depending upon the vertical position of the corresponding vibrator levers. Each connector is attached to a harness lever 22 and the latter in turn is connected by an appropriate linkage to harness 60 frame 23.

The bottom of shaft 16 extends into a bearing 24 secured to the side of the loom and said shaft has secured thereto a collar 65 25 through which extends a driving pin 26,

carried by a cap 27 slidable in a vertical direction along the shaft 16. Said pin 26 is designed to enter a recess in the driving bevel gear 28 which meshes with another gear 29 secured to a short shaft 30. Shaft 70 30 extends through the bearing member 24 and projects toward the center of the loom. Under normal operation each rotation of the shaft 30 will be accompanied by a rotation of shaft 16 through the bevel gears already 75 described.

Power for driving the loom may be derived from a motor M located at the opposite sides of the loom. I do not wish to be limited to any particular form of drive 80 for the loom and have shown the motor herein as a so-called start and stop motor having a pinion 40 to mesh directly with large gear 41 on bottom shaft 42. The bottom shaft is supported by proper bearings 85 and is given a complete revolution every other pick of the loom. Two separate and independent picking arms are secured to shaft 42, one of which 43 is adjacent the driving unit while the other arm 44 is adjacent the head motion end of the loom. Said picking arms extend in opposite directions so that but one of them is in down or operative position at a time, the arm 43 90 cooperating with the picking cam 45 which is connected operatively to a picker stick 46, while the arm 44 cooperates with a picking cam 47 and by appropriate mechanism is 95 operatively connected to the picker stick 48 located at the head end of the loom.

As the bottom shaft rotates during normal operation of the loom the picker stick 46 will be given a shuttle propelling motion on alternate picks of the loom while the picker stick 48 will be given a shuttle propelling motion on the intervening picks. On a loom of the type shown herein where there may be drop boxes at one end only of the loom it is desirable that the picker sticks act in alternation as described. The 105 lay L is driven by a crank shaft 50 deriving motion from the large gear 41 by means of a smaller gear 51 half as large as said driving gear.

The parts already described are of common construction and of themselves form no part of my present invention. The picking is effected as described and the shaft 16 is given a rotation every pick of the loom while the crank shaft 50 extends substantially parallel to them above the bottom shaft and by means of the described gearing acts to move the lay L back and forth by means of connectors 52 once for every pick of the loom.

In carrying my invention into effect I provide improved means for communicating driving power from the source of power to the upright shaft 16. Accordingly, in carrying my invention into effect, I provide 130

an auxiliary shaft 60 which rotates in bearings 61 and 62 located, respectively, adjacent the driving and head ends of the loom. The large elliptical gear 63 is secured to the bottom shaft 42 preferably as close to the driving gear 41 as possible, although I do not wish to be limited to the particular position for the elliptical gear 63 as set forth as it will be sufficient for the purposes of 5 my present invention if said crank is secured to the bottom shaft adjacent that end of the loom where the driving unit is located. Said elliptical gear meshes with a corresponding pinion 64 half as large as the elliptical gear, the purpose of this specified 15 ratio being to give the auxiliary shaft 60 a rotation every pick of the loom, it being remembered that the bottom shaft 42 rotates every other pick of the loom. Should the 20 bottom shaft rotate every pick of the loom the gears 63 and 64 will be of equal size.

The right hand end of the auxiliary shaft 60 as shown in Figs. 1 and 2 is extended to the right of the bearing 62 and into a coupling member C shown in detail in Fig. 3.

A key K extends into a slot formed in a short shaft 30 and also into another slot formed in the right hand end of the auxiliary shaft 60 and the coupling is made in 30 two parts 65 and 66 which are held together by bolts 67. By means of this coupling motion from the shaft 60 is communicated to the upright shaft 16.

In the operation of my invention as thus far described motion is communicated to the auxiliary shaft at a point between the source of power and the picking arm 44 and as shown herein at a point between the source of power and also picking arm 43, although 35 I do not wish to be limited to this latter arrangement. As the loom operates, therefore, any twist in the bottom shaft 42 which may result from the action of the picking at the head end of the loom will have no effect 40 whatever on the character of motion communicated to the head H, because of the fact that the part of the bottom shaft which is subjected to the twisting does not transmit power from the driving unit to the auxiliary 45 shaft.

As previously stated, I find the upright shaft is so located that in order to drive the same conveniently by means of an auxiliary shaft such as shown herein it is necessary to 50 have the axis of said auxiliary shaft so located as to lie within the path of movement of the picking arms 43 and 44. In order that there may be no interference on the part of the picking arms and the auxiliary shaft 55 I provide the latter with a plurality of offsets 70 and 71 which correspond, respectively, with the picking arms 43 and 44. Said offsets are preferably on the same side 60 of the axis of the shaft 60 and are of sufficient extent to permit the picking arms to

move in their normal paths of motion without interference.

In Figs. 6 to 8 I have shown diagrammatically the relation between the picking arms and the offset located at the driving 70 end of the loom. The parts are so related that they will assume the position shown in Fig. 6 when the picking arm 43 is extended toward the axis of the shaft 60, the offset 70 being turned away from the arm 43.

As the arm and auxiliary shaft turn in the directions indicated by the arrows in Fig. 7 the offset 70 will move downwardly and to the right toward the bottom shaft 42. As shown in Fig. 8 the offset will be in its 80 nearest position with respect to the bottom shaft 42 while the picking arm will be in a vertical position. As the picking arm continues to rotate for another 90° of revolution of the bottom shaft or for another half pick 85 of the loom it will assume the position diametrically opposite from that shown in Fig. 6 and the offset 70 will have moved around through 180° so that said offset will assume the position shown in Fig. 6 when the picking arm 43 is turned away from the offset.

As the bottom shaft continues to rotate the offset will be given another complete revolution and will approach the position shown in Fig. 6 as the picking arm 43 moves upwardly toward the auxiliary shaft. In this way the picking arm 43 is permitted to move without interruption and the offset 70 will always be turned away from the picking arm when the latter is moving in the vicinity of 90 the auxiliary shaft.

In the diagrammatic Figs. 9 to 11 I have indicated the relation of the parts in a loom wherein each picker stick is given a shuttle propelling movement each pick of the loom, 105 as on a so-called pick and pick loom. It will be seen that the picking arms 80 and 81 extend in opposite directions with respect to a bottom shaft 82, but the rates of speed of the bottom shaft 82 and the auxiliary shaft 110 60 will be substantially the same as in the previously described instance, so that for each half revolution of the shaft 82 the auxiliary shaft will make a complete revolution, the effect of this being to have the crank 70 115 turned away from the picking arms 80 and 81 when either of the latter is in the vicinity of the auxiliary shaft 60.

On other styles of pick and pick looms of the so-called equal geared type wherein the gears 41 and 51 are replaced by gears having equal numbers of teeth, the bottom shaft will be given a complete revolution every pick of the loom, but as this is the same rate of speed at which the auxiliary shaft turns, offset 70 120 will always be in a position to clear the picking shoe.

As shown in Fig. 5 the shaft 60 is provided with two keyways 90 and 91, respectively, one of which receives a key 92 which 125

enters a slot 93 in the hub of pinion 64. It will be understood by reference to the dia-
grammatic Figs. that the picking arm 43
will clear the offset when the arm is in any
5 one of a plurality of adjusted positions
with respect to the bottom shaft within a
limited range of adjustment, as it is not nec-
essary for the line joining the center of the
offset 70 and passing through the axis of
10 the shaft 60 to pass in every instance cen-
trally through the picking arms 43 and
44. As shown in Fig. 6, for instance, the
arm 43 could be in a somewhat lower pos-
ition than that shown and still be able to
15 clear the offset 70 when turning in the di-
rection of the arrow. For larger adjust-
ments, however, it may be desirable to shift
the pinion 64 relatively to the auxiliary
shaft 60 and place the key 92 in the slot 91.
20 A corresponding adjustment would of course
be made on the elliptical gear 63, but as
such adjustments between the bottom shaft
and the short shaft are well understood they
are not illustrated herein.
25 From the foregoing it will be seen that I
have provided a simple means for prevent-
ing the twisting of the bottom shaft from
interfering with the proper operation of the
head motion by using an auxiliary shaft
30 which derives its driving power from the
bottom shaft at a point very close to the
motor M and in such a position as not to
be affected by any twisting which may occur
in shaft 42. It will also be seen that al-
35 though the upright shaft is placed too close
to a vertical plane passing through a bottom
shaft to prevent the use of straight auxiliary
shaft, yet clearance is provided with the
picking arms by offsets in the auxiliary
40 shaft, the timing being such that the offset
will always be turned away from the pick-
ing arm when the latter is in proximity to
the auxiliary shaft, so that the arm may
pass through the space defined by the offset.
45 Furthermore, it will be seen that a relatively
large range of adjustment between the gears
63 and 64 is permitted so that the relative
timing of the head with respect to the bot-
tom shaft may be adjusted without disturb-
50 ing the relation between the picking arms
and their respective offsets. Furthermore,
it will be seen that whether the loom be of
the usual type wherein the bottom shaft ro-
tates once for every second pick of the loom
55 or whether the bottom shaft operates as in
an equal geared loom to rotate once every
pick the relation of the offsets and the pick-
ing arms will still be preserved.
Having thus described my invention it
60 will be seen that changes and modifications
may be made therein by those skilled in the
art without departing from the spirit and
scope of the invention and I do not wish to
be limited to the details herein disclosed, but
65 what I claim is:

1. In a loom having a picking mechanism
at each end thereof, a harness controlling
mechanism for one end thereof, a source of
power located at the other end of the loom,
and a shaft operatively connected to the 70
source of power and extending across the
loom to operate the picking mechanisms, in
combination, an auxiliary shaft substantial-
ly parallel to the first named shaft and hav-
ing driving operative connection with the 75
harness controlling mechanism only, and
driving connections between the two shafts
including a part carried by the first named
shaft located on that side only of the loom
adjacent the source of power. 80

2. In a loom having a picking mechanism
at each end thereof, a harness controlling
mechanism for one end thereof, a source of
power located at the other end of the loom,
and a shaft operatively connected to the 85
source of power and extending across the
loom to operate the picking device, in com-
bination, an auxiliary shaft having operative
connection with the harness controlling de-
vice only and having driving connection 90
with the first named shaft at a point along
said first named shaft adjacent the source
of power, said auxiliary shaft being inde-
pendent of the first named shaft at all other
points. 95

3. In a loom having a picking mechanism
at each end thereof, a harness controlling
mechanism for one end thereof, a source of
power located at the other end of the loom,
and a shaft operatively connected to the 100
source of power and extending across the
loom to operate the picking device, in com-
bination, an auxiliary shaft having opera-
tive driving connection with the harness
mechanism only, meshing gears one of 105
which is located on each shaft, said gears
being adjacent the source of power and com-
municating power from the first named
shaft to the auxiliary shaft, said shafts ex-
tending across the loom from the meshing 110
gears and independently of each other. 115

4. In a loom having crank and bottom
shafts geared together and extending across
the loom, a harness controlling mechanism
for one end thereof, and a source of power
located at the other end of the loom, a shaft 120
operatively connected to the source of power
and extending across the loom to operate
the picking device, in combination, a third
shaft operatively connected to one of the 125
other shafts at a point adjacent the source
of power and extending across the loom in-
dependently of the other shafts and opera-
tively connected to the harness controlling
mechanism.

5. In a loom having a picking mechanism
at each end thereof, a harness controlling
mechanism for one end thereof, a source of
power located at the other end of the loom,
a shaft operatively connected to the source 130

- of power and extending across the loom to operate the picking device, and an upright shaft to drive said harness controlling mechanism, in combination, a driving shaft 5 for the harness mechanism only extending across the loom parallel to the first named shaft and operatively connected to the lower end of the upright shaft and having driving connections with the first named shaft 10 at that part of said first named shaft only which is adjacent the source of power.
6. In a loom having a picking device at each end thereof, a harness controlling mechanism for one end thereof, a source of 15 power located at the other end of the loom, a shaft operatively connected to the source of power and extending across the loom to operate the picking devices, an upright shaft to drive said harness controlling mechanism, and a comparatively short shaft extending parallel to the first named shaft and operatively connected to the upright shaft, in combination, an auxiliary shaft 20 forming an extension of the short shaft extending across the loom and having driving connection with the first named shaft at one part only of the latter adjacent the source of power.
7. In a loom having a shuttle propelling device at each end thereof, a shaft extending 30 across the loom, a pair of picking arms secured to said shaft, one adjacent each end of the loom, a harness controlling mechanism located at one side of the loom, a source of power located at the opposite side of the loom, and an auxiliary shaft extending parallel to the first named shaft and deriving power from the first named shaft at a point adjacent the source of power, said auxiliary 35 shaft having an offset defining a space through which one of the picking arms may move.
8. In a loom having a shuttle propelling device at each end thereof, a shaft extending 40 across the loom, a pair of picking arms secured to said shaft, one adjacent each end of the loom, a harness controlling mechanism located at one side of the loom, a source of power located at the opposite side 45 of the loom, and an auxiliary shaft extending parallel to the first named shaft and deriving power from the first named shaft at a point adjacent the source of power, said auxiliary shaft having an offset defining a space 50 through which one of the picking arms may move, the driving connections between the shafts including two meshing gears one of which is twice the size of the other.
- 60 9. In a loom having a shuttle propelling device at each end thereof, a shaft extending across the loom, a pair of picking arms secured to said shaft, one adjacent each end of the loom, a harness controlling mechanism located at one side of the loom, a source of power located at the opposite side 65 of the loom, said shaft having a complete revolution every second pick of the loom, an auxiliary shaft operatively connected to the harness controlling mechanism, a relatively small gear on the auxiliary shaft, a second gear meshing therewith and of twice the number of teeth secured to the first named shaft, and an offset formed in the auxiliary shaft defining a space through 70 which one of the picking arms may pass.
10. In a loom, a driven shaft having a picking arm thereon moving through a given path of action, a harness controlling mechanism, a shaft operatively connected to said 75 mechanism and having the axis thereof located within the path of action of the picking arm, and an offset formed in the auxiliary shaft defining a space through which the picking arm passes when adjacent the auxiliary shaft.
11. In a loom having a source of power and a harness controlling mechanism, a pair of shafts operatively connected together one of which is connected to the harness controlling mechanism and the other of which is connected to the source of power, a picking 80 arm are located on one of the shafts, and an offset in the other shaft defining a space through which the picking arm may pass.
12. In a loom having a source of power and a harness controlling mechanism, a pair of shafts operatively connected together one of which is connected to the harness controlling mechanism and the other of which is connected to the source of power, a picking arm located on one of the shafts, and an offset in the other shaft defining a space 85 through which the picking arm may pass, said gears being driven in timed relation so that the offset will always be extended away from the picking arm when the latter is adjacent the shaft in which the offset is located.
13. In a loom having a source of power located at one side of the loom and a harness controlling mechanism on the other side of the loom, a revolving picking arm, a shaft, means to communicate power from the source of power to the shaft at that side of the loom only adjacent the source of power, and an offset formed in the shaft defining a space 90 through which the picking arm may pass.
14. In a loom having a source of power located at one side of the loom and a harness controlling mechanism on the other side of the loom, a picking arm moving through a fixed path, a shaft, means to communicate power from the source of power to the shaft at that side of the loom only adjacent the source of power, and an offset formed in the shaft defining a space through which the picking arm may pass.
15. In a loom having a driving unit at one end thereof and a harness controlling 100

mechanism at the other end thereof, a driving gear operatively connected to the driving unit on that side of the loom adjacent to the driving unit, a shaft extending across the loom and operatively connected to the harness controlling mechanism, a gear secured to the shaft and meshing with the first

named gear, and means to secure the second named gear to the shaft in any one of a plurality of positions.

10

In testimony whereof I have hereunto affixed my signature.

OSCAR V. PAYNE.
